US0D1051055S

(12) **United States Design Patent** (10) **Patent No.:** **US D1,051,055 S**
(45) **Date of Patent:** **** Nov. 12, 2024**

(54) **MULTI-FUNCTION INVERTER**

(71) Applicant: **Shenzhen Zhongyuan Network Technology Co., Ltd.**, Shenzhen (CN)

(72) Inventor: **Shunan Wu**, Henan (CN)

(73) Assignee: **Shenzhen Zhongyuan Network Technology Co., Ltd.**, Shenzhen (CN)

(**) Term: **15 Years**

(21) Appl. No.: **29/956,301**

(22) Filed: **Aug. 6, 2024**

(51) LOC (14) Cl. **13-02**

(52) U.S. Cl.

USPC **D13/110**; D13/103

(58) **Field of Classification Search**

USPC D13/110, 103, 106, 107, 112, 113, 116

CPC H02J 7/0044; H02J 7/342; H02M 7/003

(57) **CLAIM**

The ornamental design for a multi-function inverter as shown and described.

DESCRIPTION

FIG. 1 is a front, top, and left perspective view of a multi-function inverter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, bottom, and right perspective view thereof. The broken lines shown in the drawings represent portions of the multi-function inverter that form no part of the claimed design.
